US00D745862S

(12) **United States Design Patent**
Otani et al.

(10) **Patent No.:** US D745,862 S
(45) **Date of Patent:** ** Dec. 22, 2015

(54) **COMBINED HEADPHONE AND AUDIO PLAYER**

(71) Applicant: **Sony Corporation**, Tokyo (JP)

(72) Inventors: **Yusuke Otani**, Kanagawa (JP); **So Morimoto**, Saitama (JP); **Taku Yaegashi**, Tokyo (JP)

(73) Assignee: **Sony Corporation**, Tokyo (JP)

(**) Term: **14 Years**

(21) Appl. No.: **29/496,002**

(22) Filed: **Jul. 8, 2014**

Related U.S. Application Data

(63) Continuation-in-part of application No. 29/421,750, filed on Sep. 14, 2012, now Pat. No. Des. 709,051, which is a continuation-in-part of application No. 29/371,743, filed on Aug. 18, 2011, now Pat. No. Des. 667,817.
